UNITED STATES PATENT OFFICE.

JOHN G. FISHER, OF MCLEAN, VIRGINIA.

BUCKLE.

1,403,111.

Specification of Letters Patent. Patented Jan. 10, 1922.

Application filed August 12, 1921. Serial No. 491,207.

To all whom it may concern:

Be it known that I, JOHN G. FISHER, a citizen of the United States, and a resident of McLean, in the county of Fairfax and 5 State of Virginia, have invented certain new and useful Improvements in Buckles, of which the following is a specification.

The present invention relates in general to buckles, and more particularly to buckles 10 having a buckle retainer adapted to prevent displacement from the buckle either horizontally or vertically.

The object of the invention is to provide a buckle of this character which is of extremely simple and durable construction, the major elements of the buckle being for the most part formed of a single piece of metal, and which embodies a buckle retainer for 15 permanently and positively preventing lateral or horizontal as well as vertical displacement of the buckle while in no way detracting from the clasping or clamping action of the buckle or from its features of comfort or attractiveness.

20 Other objects and advantages of the invention reside in certain novel features of construction, combination and arrangement of parts which will be hereinafter more fully described and particularly pointed out in the 25 appended claim, reference being had to the accompanying drawings forming part of this specification, and in which:

Figure 1 is a perspective view, illustrating one embodiment of the invention;

30 Figure 2 is a view in horizontal section of the embodiment of the invention shown in Figure 1;

Figure 3 is a view in vertical section on line 3—3 of Figure 2.

40 Referring to the drawings wherein for the sake of illustration is shown the preferred embodiment of the invention, and more especially to Figures 1 and 3, the numeral 10 designates generally the frame of the buckle,

45 which is constructed of a single piece of metal and which includes a body portion 11, an upper side flange 12 and a lower side flange 13, the side flanges extending approximately at right angles to the body portion 50 and defining with the channel for the representation of a buckle, designated at 14.

A U-shaped buckle retainer 15 is integrally formed with the lower side flange 13 and extends upwardly therefrom across the channel defined by the side flanges 55 toward the upper side flange 12. The buckle retainer includes a pair of arms

16 which define a socket 17 adapted to receive the shank of a button, designated at 18. The button is secured to the trousers 60 or other garment and the head thereof is received in the channel defined by the flanges, the shank being firmly engaged by the arms which define the socket whereby the buckle is retained against movement, 65 either laterally or vertically, thus preventing displacement of the belt connected with the buckle.

The side flanges adjacent one end thereof are provided with inclined cam grooves or 70 slots 19 in which a sliding bar 20 operates. The free end of the buckle 14 is engaged by the sliding bar to retain the buckle in position. The other end of the buckle is connected to the swinging cross bar 21 which 75 is pivotally mounted on the side flanges of the frame at the end thereof opposite the inclined slot 19.

In use, the wearer having adjusted the belt on the garment by moving the free end 80 thereof through the channel defined by the body portion and side flanges of the frame and by engaging the sliding bar with the frame, next grasps the frame and moves it so that the arms 16 of the buckle retainer 15 85 extend on the opposite sides of the buckle 18, engaging it and causing the shank thereof to be seated in the socket 17. When the button 15 is thus engaged by the button retainer the buckle and the belt to which it is 90 connected is firmly held in position and will not be displaced either laterally or vertically.

Moreover the buckle retainer is formed integral and of the same material as the elements of the buckle thus simplifying the manufacture and enabling the buckle to freely participate of its buckling or clasping action and leaving it wholly attractive and operable.

100 I claim:

A belt buckle comprising a frame constructed of a single piece of resilient metal and including a body portion having side flanges defining a channel adapted to receive 105 one of the ends of the belt, one of said side flanges having an integrally U-shaped buckle retainer extending toward the other side flange and having arms defining a socket adapted to receive the shank of a 110 button and prevent displacement of the buckle horizontally or vertically.

JOHN G. FISHER.
